UNITED STATES PATENT OFFICE.

JAMES SPRUCE, OF WATERBURY, CONNECTICUT, ASSIGNOR TO THE SCOVILL MANUFACTURING COMPANY, OF SAME PLACE.

CURTAIN-POLE JOINT.

SPECIFICATION forming part of Letters Patent No. 327,834, dated October 6, 1885.

Application filed July 27, 1885. Serial No. 172,772. (No model.)

To all whom it may concern:

Be it known that I, JAMES SPRUCE, of Waterbury, in the county of New Haven and State of Connecticut, have invented a new 5 Improvement in Curtain-Pole Joints; and I do hereby declare the following, when taken in connection with accompanying drawings and the letters of reference marked thereon, to be a full, clear, and exact description of the 10 same, and which said drawings constitute part of this specification, and represent, in—

Figure 1, a top view showing the two shanks screw-threaded and standing in diametrically opposite positions, broken lines at the right 15 indicating different angles to which the shanks may be turned with relation to each other; Fig. 2, a side view of the same; Fig. 3, a horizontal section of the same; Fig. 4, a vertical central section of the opposite sides of the 20 joints; Fig. 5, a modification of the construction of the outer shell.

This invention relates to an improvement in the connection between the parts of the pole employed over windows, from which curtains are suspended. The object of the joint 25 is that a bend may be made in the pole—as for bay-windows or other points where the pole is required to be turned away from a direct line. To cut the pole and abut the joint, so 30 as to make a good finish, is a very difficult and expensive operation. Again, such a cutting and fitting requires the work of a skilled mechanic, which in many places it is inconvenient to obtain. To overcome these difficulties 35 a joint something in the character of a hinge has been provided, one part attached to one end of one part of the pole and the other part of the joint attached to the corresponding end of the adjacent part, and so that one part may 40 be turned to any desirable angle to the other. This enables the cutting of the ends of the pole substantially square, and avoids the fitting and expensive work necessary to attain a good angle. It is to this peculiarity of joint 45 that the invention particularly relates; and it consists in a shell, substantially circular in horizontal section, having a screw fixed at one point, projecting radially therefrom, and in the said horizontal plane, and also constructed with a horizontal slot extending par-

tially around the said shell opposite the said fixed screw, combined with a ring within said shell, having a second screw rigidly fixed to it and projecting radially therefrom through said horizontal slot, and in the same plane as 55 the screw fixed to the shell, as more fully hereinafter described.

In the construction of the joint I prefer to make the shell in spherical form. A represents one part, and B the other part, of the 60 shell; and I prefer to make the shell in three parts, C being the third part. This third part, C, is in the form of a ring, and the parts A B are attached to each edge of the ring, so that the three parts together form substantially a 65 sphere, as seen in Fig. 2.

From the ring C a screw or equivalent shank, D, extends radially and in the diametrical plane of the ring or sphere. The screw is rigidly fixed to the ring, so that it becomes a 70 permanent part of it. This may be done by inserting the screw through the ring and riveting it thereon, as indicated in Fig. 3; or it may be soldered or brazed thereto.

In the ring opposite the screw D a slot, E, 75 is formed circumferentially, and in the same plane as the screw D, and it extends preferably about one-third of the circumference of the ring. Inside this ring or shell a ring, F, is arranged, so as to fit closely upon the inside 80 of the shell, and guided thereby is permitted to rotate within the shell. To this shell a screw, G, is rigidly fixed, in like manner as is the screw D to the outer shell, the screw G extending radially from its ring and through 85 the slot E in the shell or outer ring, and so that the two screws stand in the same plane, as seen in Fig. 2, the two screws being at right angles to the axis, about which the shell or ring may turn, the one upon the other. 90 Preferably I make the inner ring complete; and that it may not interfere with the inner end of the screw D, fixed in the shell, I construct the inner ring with a slot, H, in the same plane as the slot E in the outer shell, 95 and so that in the movement of the shell upon the ring, or vice versa, the inner end of the screw will not interfere with the inner ring. This inner ring, however, need not extend entirely around the inside of the shell, it only 100

eing necessary that it shall take a bearing sufficient in extent to support the ring against diametrical thrust upon the screw G, fixed to it, or upon the screw D, fixed to the outer shell.

In the construction, as illustrated in Figs. 1, 2, 3, and 4, the central portion, C, has its upper and lower edge turned outward, and the corresponding edge of the parts A, B are turned, respectively, over the projecting edge of the part C, and so as to form a bead upon the outside; but the two parts A, B may be secured to the ring by soldering or otherwise. The parts A, B serve only as ornamental portions, as the outer ring, C, and the inner ring, F, with their respective fixed screws, make the connection between the two parts of the pole.

The central portion, and to which the one screw D is fixed, may be made integral with the part A, as seen in Fig. 5, so that the shell complete will be formed in two parts, instead of three, as before described; but I prefer to make the central portion in two rings, both lotted, the outer ring having the screw rigidly fixed to it, and the inner ring having a screw rigidly fixed to it, to work through the lot in the outer ring. By this construction the two screws are maintained in the same plane.

In applying the joint, the screw or shank D is introduced into the end of one part of the pole and the screw G into the corresponding end of the other part; then the one part may be turned upon the other in either direction, as indicated in broken lines, Fig. 1, to bring it to the required angle.

The two parts A, B, which practically form overs to close the ring, may be made of any desirable style or shape, giving to the joint

more or less ornamentation according to the amount of work applied.

It will be understood from the foregoing that I do not claim, broadly, the ball-like joint between adjacent ends of the parts of a curtain-pole; but

What I do claim is—

1. The herein-described joint for curtain-pole, consisting of the outer ring or shell having a shank, D, rigidly fixed thereto and extending therefrom in a radial direction and in a horizontal plane, the shell constructed with a slot, E, opposite the fixed shank and in the same horizontal plane, combined with a ring, F, arranged within the shell and in the plane of the before-mentioned slot, the said inner ring having a shank, G, rigidly fixed thereto and extending radially therefrom through the said slot E in the outer shell, and in substantially the same plane as the shank D of the shell, substantially as described.

2. The ring C, constructed with a rigid shank, D, projecting radially therefrom, the said ring constructed with a slot, E, opposite the said shank and in the plane of the ring, a ring, F, arranged within said ring C, and adapted to freely turn therein in the plane of the ring, the said ring F, constructed with a rigid shank, G, projecting radially therefrom and through the said slot E in the ring C, the two parts A, B, attached to the respective edges of the ring C to substantially close the ring, substantially as described.

JAMES SPRUCE.
